UNITED STATES PATENT OFFICE

HANS ERNST AND LESTER F. NENNINGER, OF CINCINNATI, OHIO, ASSIGNORS TO THE CINCINNATI MILLING MACHINE COMPANY, OF CINCINNATI, OHIO, A CORPORATION OF OHIO

MILLING MACHINE

Application filed September 23, 1930. Serial No. 483,860.

This invention relates to improvements in milling machines and has particular reference to the mechanism for bracing and supporting the cutter to increase the accuracy of the product of such machines.

In the performance of milling operations it is frequently necessary that the cutter be disposed at an appreciable distance from the column of the machine. As a result in the feeding of the metal work piece forcefully against the cutter there is a tendency to flexing or springing of the arbor bearing the cutter. In the attempt to reinforce the arbor use has been made in the past of supplemental brace members known as overarms which are carried by the machine column and ordinarily overlie the arbor being coupled therewith by a suitable support member. In some instances a single overarm and in others a double overarm has been employed. Analysis of prior art structures, however, discloses the fact that the double overarm, as hitherto employed, has not provided a sufficiently rigid brace for the cutter due to the twisting strain exerted thereagainst. In the conventional double overarm this twisting strain is sufficient to overcome the clamping force by which the overarms are secured to the pendant and cause a slight rotational movement of the overarms in their bores with the result that when the twisting strain ceases, the parts do not return to normal position but on the other hand have received a somewhat permanent lateral set. This action is particularly accentuated if there is looseness in the clamping of either of the overarm members in the column or the clamping of the support thereto.

It is, therefore, the purpose of the present invention to provide a novel and improved structure in which the parts will be positively interlocked into a unitary rigid bracing member, in which the cross section of the parts will be such as to prevent twisting strain and in which any relative twisting or rotating, one part within or about the other, will be entirely prevented and eliminated.

A further object of the invention is the provision of a structure which will relieve the clamping means previously employed from

the necessity of resisting the various twisting forces exerted by movement of the work table so that they may serve solely as position controlling members thus reducing the tension necessary to be applied to such members and the liability of stripping of threads or breaking of parts in the attempt to obtain desired rigidity.

Certain employments of the inventive principles for accomplishment of the foregoing results have been illustrated in the accompanying drawings and it will be understood that we may make any modifications in the specific structural details hereinafter shown and described within the scope of the appended claim without departing from or exceeding the spirit of the invention.

These and other objects are attained by the means described herein and disclosed in the accompanying drawings, in which:

Figure 1 is a perspective view of a standard milling machine having the invention embodied therein.

Figure 2 is an enlarged sectional view taken on line 2-2 of Figure 1.

Figure 3 is a sectional view, similar to Figure 2, showing a modification of the invention.

Figure 4 is a sectional view, similar to Figures 2 and 3, showing another modification.

Figure 5 is a sectional view taken on line 5-5 of Figure 4.

Figures 6 and 7 are diagrammatic views of the effect of the distortional forces involved herein.

In Figure 1 of the drawings is shown a standard milling machine comprising the usual base plate 10 having uprising therefrom a vertical column 11 to which is reciprocably secured the knee 12 for supporting a transversely movable table 13 carried thereby. The usual feed change box 14 and spindle feed control 15 are also carried by the column 11. All of the foregoing details are usual construction and form no part of this invention.

The upper end 16 of the column 11 is enlarged for the purpose of providing therein a pair of suitable perforations for receiving the overarms, such as 17 and 18. These per-

forations are formed complementary to the peripheral contour of the overarms and the fit between the parts should be such as to permit longitudinal adjustment of the overarm with respect to the column without any lateral play. Clamp means have been provided for rigidly securing the overarms in the column after longitudinal adjustment and may take the form of set screws, such as 19 and 20, or other suitable known means for frictionally binding the overarms in the column.

10 A spindle 21 is journaled in the column beneath the overarms for actuating an arbor or tool support 22 extending therefrom having a cutter 22' mounted thereon.

15 The overarms 17 and 18 are provided for the purpose of supporting the tool arbor against the reaction of the cutter with the work and for this purpose a support member 20 or pendant 23 having a pair of perforations 24 and 25, similar in cross section to those in the column, is mounted on the free ends of the overarms. This support depends from the overarms and is provided with a bearing 26 for receiving and journaling the outboard end of the cutter arbor 22. A pair of slots 27 and 28 intersecting the perforations 24 and 25 divide the upper part of the pendant into three sections, 29, 30 and 31,

25 shown more particularly in Figure 2. A transverse bore extends through these sections for receiving a suitable clamping member, such as a bolt 32 having a nut 33 threaded on the end thereof. From Figure 2 it will be apparent that upon tightening the nut the portions 29 and 31 will be drawn toward the intermediate portion 30 thereby frictionally binding the pendant to each overarm.

40 From the foregoing description it should now be apparent that an arbor support structure has been provided comprising a pair of overarms longitudinally, adjustably mounted in the column with means for securing them in the column, and which have attached to their free ends an arbor support or pendant which is longitudinally adjustable thereon and may be clamped thereto in any position, the pendant having a bearing for receiving the free end of the cutter arbor to thereby support the same against lateral movement.

45 In order that the invention may be more clearly understood reference may be had to Figures 6 and 7 in which is diagrammatically shown the effect of the forces herein involved which tend to distort the arbor supporting structure. In Figure 6 is shown a pendant mounted on the end of a double overarm, the members of which are cylindrical in cross section. It has been found that if a force, such as P, is applied in the direction of the arrow, which would be similar in direction to the reaction set up in the arbor by a cutter in engagement with a work piece, that

the movement being in the form of rotation substantially about the neutral axis X. The effect of this movement is to cause a slight rotation of the pendant 23 relative to the overarms 17 and 18, which evidently is due to the twisting resistance of the arms being greater than the frictional clamping force between the arms and their sockets. The amount of this movement may be detected by drawing a hair line, such as 50-50', in the parts at assembly, as shown in Figure 7. After the application of a lateral force, such as P, the marks will be relatively displaced, as shown in Figure 6. The result of this relative movement is to effect a lateral set 80 which prevents the parts from returning to normal position upon cessation of the force P. In other words, the pendant and arms have slipped relative to one another and the pendant has taken a new frictional grip 85 on the overarms.

90 It may be possible that instead of the relative movement taking place between the pendant and the overarms as previously described, that the frictional clamping of the overarms in the column may be weaker than in the pendant and the relative movement will, therefore, take place between the overarms and the column. In fact in such a structure where there are four joints and each a 95 frictionally clamped one, it is evident that when stress is put upon the whole structure the weakest of these joints will fail and permit relative movement between the parts thereof.

100 Due to the nature of the structure wherein the overarms and the pendant must be maintained in parallelism to preserve the accuracy of the machine any slippage of the joints in such a structure will disturb the whole alignment thereof and prevent the accomplishment of accurate work upon the machine. Furthermore, any relative movement of the nature described is not self-compensated for in any subsequent movements of the machine 105 and can only be corrected by loosening all the parts to permit return to normal position and then reclamp them.

110 It is, therefore, one of the main objects of this invention to overcome all of the above difficulties by providing an overarm structure in which the members are so formed as to eliminate any possibility of relative movement between the parts, such as might occur with round overarms, while still maintaining 115 all the relative adjustments as heretofore. One embodiment of this invention is shown in Figures 2 and 3 in which the overarms have been given an irregular cross section by the use of keys 35 and 36 which may be integrally secured to the overarms 17 and 18 respectively in any suitable manner. These keys extend the full length of the overarms and the perforations in the column as well as in the pendant are so formed as to properly

receive them. By the application of this invention relative rotative movement between the overarms and the column or between the overarms and the pendant support will be 5 positively prevented without depending upon the resistance of a frictional clamp thereby causing the cutter reaction to be directly absorbed by the torsional resistance of the overarms. In other words, if relative movement is positively prevented between the parts forming each connection, the reaction 10 on the cutter arbor will be transmitted to the pendant which acting on one end of the overarms will tend to rotate them in their 15 column sockets but the positive connection in the column will prevent this rotation and thereby cause a twisting movement to be set up which will be resisted by the torsional resistance of the overarm. This positive 20 connection also relieves the burden on the clamping bolts 19 and 20, as well as 32, while at the same time permitting adjustment of the overarms in the column, as well as adjustment of the pendant upon the over- 25 arms.

In Figure 3 a modification is disclosed in which the overarms, such as 37, are given a cross section which is other than circular and which serves to prevent movement of the 30 arbor support on the overarms after it has been secured thereto as by the bolt 32. In the use of this modification it is to be understood that the perforations in the column for receiving these overarms will be similar in 35 cross section to those in the pendant whereby longitudinal adjustment of the overarms will be permitted with respect to the column, as well as adjustment of the pendant along the overarms.

40 A further modification is disclosed in Figures 4 and 5. In this device circular overarms, such as 38 which have been provided with a flat side, are employed and extend through suitable perforations 39 formed in the arbor support 40. The arbor support is 45 provided with slots, such as 27 and 28, and a transverse bore for receiving the clamping bolt 32. In addition to these the arbor support is provided with recesses 41 in which clamp blocks 42 are received. These blocks 50 are provided with aligned perforations 43 through which suitable clamping means, such as the draw bolt 44, extends for drawing the clamp blocks toward one another. 55 These blocks may initially have a circular cross section and then shaped on the upper surface with an angular face 45 which cooperates with the angular faces 46 formed on the overarms 38. In this construction the 60 clamp blocks 42 constitute positive means, which in addition to the friction means, positively secure the arbor support to the overarms and prevents relative movement thereof. Attention is invited to the fact that in 65 this modification as in the other the face 46

will extend the full length of the overarms; and the clamping means, such as the blocks 42, will also be provided in the column for securing the overarms therein.

From the foregoing it should now be apparent that each embodiment of this invention provides positive means whereby the arbor support is positively held and prevented from relative movement with respect to the overarms and that the overarms are 70 positively held against relative movement with respect to the column and that these results have been obtained without interfering with the relative adjustment of the overarms with respect to the column or of the 75 pendant with respect to the overarms.

That which is claimed is:

In a milling machine the combination of a support, a pair of overarms extending through and beyond the support, an arbor 80 extending from the support and positioned below the overarms, an arbor support receiving the free ends of the overarms and arbor, the arbor support having slots therein in alignment with the overarms, means extending through the arbor support for drawing the sections thereof toward one another for frictionally binding the overarms in the arbor support, the arbor support being further provided with recesses below the 85 overarms, clamp blocks received in the recesses having angular faces formed thereon, angular faces formed on the overarms co-operating with the angular faces on the clamp blocks, the arbor support and clamp blocks 90 having bores formed therein in axial alignment, and means extending through the aligned bores for drawing the clamp blocks toward one another and for causing a locking engagement of the angular faces on the 95 wedge blocks and overarms for positively locking the arbor support in position on the overarms.

In testimony whereof we affix our signatures.

HANS ERNST.
LESTER F. NENNINGER.
